UNITED STATES PATENT OFFICE.

JAMES M. STRATTON, OF SALEM, OHIO, ASSIGNOR TO THE DEMING COMPANY, OF SAME PLACE.

DESIGN FOR A BODY PORTION OF HYDRAULIC RAMS.

SPECIFICATION forming part of Design No. 32,535, dated April 17, 1900.

Application filed March 20, 1900. Serial No. 9,461. Term of patent 14 years.

To all whom it may concern:

Be it known that I, JAMES M. STRATTON, a citizen of the United States, residing at Salem, in the county of Columbiana and State 5 of Ohio, have invented and produced a new and original Design for the Body Portion of Hydraulic Rams, whereof the following is a description, due reference being had to the accompanying drawings, which form part of 10 this specification, and represent, by—

Figures 1 and 2, a side and a front elevation, respectively, of the body portion of a hydraulic ram embodying the characteristic features of my new and original design.

15 Reference being had to the accompanying drawings and the letters thereon, it will be observed that in design my form of ram comprises an enlarged cylindrical pressure-chamber A, having ends B C of substantially hemi-spherical form. Beneath the chamber A is a 20 flaring bell-shaped base or support D, also a through drive-pipe E, which bisects said

base, as shown, and delivery-ports F F at right angles to pipe E, opening from the chamber A aforesaid. At its extremity pipe E is enlarged, as shown by the letter G, and is broken by impetus and supply valve ports H I, respectively, and by an additional port J above, which latter opens directly into the pressure-chamber A, as shown. 25

This being a statement of the general outline and configuration of the main casting or body portion of a hydraulic ram constructed in accordance with my design, what I desire to claim and secure by Letters Patent is— 30

The design for the body portion of a hydraulic ram, substantially as herein shown and described. 35

In testimony whereof I subscribe my signature in the presence of two witnesses.

JAMES M. STRATTON.
